Attys.

UNITED STATES PATENT OFFICE.

RALPH J. CARNEY, OF ALLSTON, BOSTON, MASSACHUSETTS, ASSIGNOR TO CARR FASTENER COMPANY, OF CAMBRIDGE, MASSACHUSETTS, A CORPORATION OF MAINE.

FASTENER.

Application filed February 15, 1921. Serial No. 445,164.

To all whom it may concern:

Be it known that I, RALPH J. CARNEY, a citizen of the United States, and a resident of Allston, city of Boston, in the county of 5 Suffolk and State of Massachusetts, have invented an Improvement in Fasteners, of which the following description, in connection with the accompanying drawings, is a specification, like characters on the drawings representing like parts.

This invention pertains to improvements in separable fasteners. It is among the objects of the invention to provide a stud and socket fastener having conveniently operable mechanism for effecting a positive lock between stud and socket and for releasing the stud and socket from each other.

In the drawings, which show a preferred form of my invention selected for illustrative purposes:

Figure 1 is a front elevation of the fastener;

Fig. 2 is a section on the line 2—2 of Fig. 1;

Fig. 3 is a section on the line 3—3 of Fig. 2;

Fig. 4 is an end elevation of one of the parts included in the socket, and is more fully described hereinafter;

Fig. 5 is a side elevation of Fig. 4;

Fig. 6 is an end elevation of another part of the socket, more fully described hereinafter; and

Fig. 7 is a section on the line 7—7 of Fig. 6, being partly in elevation.

Referring to the drawings and to the preferred form of my invention selected for illustrative purposes, I have shown a stud including a head 7, a neck 8, a shank 9, a base 40 10 and a screw 11. The stud, as illustrated, preferably presents an abrupt shoulder between the head 7 and the neck 8, the neck 8 being preferably, as illustrated, relatively short and preferably having a relatively abrupt shoulder rearwardly thereof. The shank 9 is also preferably relatively short. The base 10 may be hexagonal or of other non-circular shape to provide a grip for a wrench when screwing the stud to its carrier, typified by the wood 12, which may be a portion of an automobile body. The base 10 preferably provides a bearing surface lying immediately rearwardly of the shank 9 and preferably perpendicular to the longitudinal 50 axis of the stud.

The preferred form of socket illustrated may be carried by a flexible fabric 13, such for instance as the curtain of an automobile. The socket may include stud-engaging jaw means typified by the projecting portions 14, 14, 14 (Fig. 4) on a preferably rotatable part 15 which, as illustrated, is preferably rotatable about an axis eccentric to the axis of the stud. Rotation of the eccentric part 15 is preferably actuated intermittently, step 65 by step, a partial rotation of say sixty degrees moving the jaws 14 from stud-engaging to stud-releasing position and conversely from stud-releasing to stud-engaging position. This intermittent rotative movement 70 may be and preferably is effected by pushing on a part projecting from and carried by the socket acting through any suitable mechanism. In the preferred form of my invention illustrated, the push button 16 is 75 provided with projections typified by the lugs 17 engaging slots 18 in the rotatable part 15. The push button 16 is also provided with projecting means typified by the bosses 20 engaging cam slots in a surrounding cam piece 19 which is not rotative. The cam piece 19 may be secured to the back plate 21 of the socket by bent-over projections 22 penetrating the back plate 21, and the socket as a whole may be secured to the socket-carrying fabric or curtain 13 by a securing casting 30 engaging the cam piece 19 and preferably provided with prongs 31 penetrating a front attaching plate 32 and back plate 21, being bent over the last-mentioned plate 90 at 33.

A spring 34 is provided between the rotative parts 15 and the push button 16 and tends to keep the push button part always in its outermost position. The cam race 95 in the cam portion 19 is engaged by the projections 20 on the push button part 16, this cam race preferably being formed as best illustrated in Fig. 7. When the socket is engaged with the stud and the parts are in their normal relation, as illustrated in Fig. 2, an inward push on the push button 16 will cause rotation of the push button 16 and the rotative part 15, which must rotate therewith by reason of the engagement through the slot 18. The rotation of the push button 16 will take place because the projections or bosses 20 thereon will be at the beginning of the inward movement at the position 40 indicated in Fig. 7. The 110

inward push on the button will cause the projection 20 to travel down the cam surface 41 until the bottom thereof is reached, at which time the boss 20 will have assumed 5 the position 42 illustrated in Fig. 7. If the push button 16 be then released, the spring 34 pressing outwardly on the push button will cause the boss 20 to assume the position 43 (Fig. 7) corresponding to the position 40 initially occupied prior to the pressing inward of the push button. The outward movement of the push button will be accompanied by sufficient rotative movement thereof occasioned by bearing of the boss 20 on the cam surface 44 to leave the parts in 15 position so that the next inward push on the button, coupled with its outward movement, will produce a further sixty degree rotative movement of the push button and the rotative part carrying the stud-engaging jaws. Assuming the socket to be locked to the stud, by reason of engagement of one of the jaws 14 (Fig. 4) behind the head of the stud, an inward push on the push button and release 20 thereof will turn the part 15 sixty degrees so that the head of the stud will lie opposite the recess 45 (Fig. 4), so that the socket may be freely removed from the stud. If now the socket be again placed over the head 25 of the stud and the push button again pressed and released, the rotative part 15, turning another sixty degrees, will bring another projecting jaw portion 14 beneath the head of the stud to effect locking engagement. Separation of stud and socket arising from bodily movement of the socket as a whole relative to the stud is prevented because the aperture in the back plate 21 of the socket preferably fits relatively closely 30 to the shank portion 9 of the stud. Pressure on the press button cannot move the socket as a whole any substantial distance axially of the stud because the back plate 21 bears against the shoulder or bearing surface at 35 the front of the base 10 of the stud.

While I have shown and described a preferred form of one embodiment of my invention, it will be understood that changes involving omission, substitution, alteration 50 and reversal of parts, and even changes in the mode of operation, may be made without departing from the scope of my invention, which is best defined in the following claims.

Claims:

55 1. A separable fastener comprising, in combination, a stud having a head and a neck, and a socket including a plurality of stud-engaging jaws and means for progressively presenting said jaws for engagement 60 with the neck of the stud.

2. A separable fastener comprising, in combination, a stud having a head and a neck, and a socket presenting a rotative part for alternate engagement and disengagement of jaws means with the neck of the stud. 65

3. A separable fastener comprising, in combination, a stud having a head and a neck, a socket presenting a projecting push button and jaw means having alternate positions of rest in locked and unlocked position relative to a stud-receiving aperture in said socket, and operating means between said push button and said jaw means for actuating said jaw means by successive pressing and release of said push button. 75

4. A separable fastener comprising, in combination, a stud having a head and a neck, and a socket including a part providing jaw means, and means for rotating said part step by step about an axis parallel 80 and eccentric to the axis of said stud. 85

5. A socket for separable fasteners, including a rotative part, a push button, a spring normally holding said push button in its projecting position and cam means operable by inward movement of said push button for turning said rotative part. 90

6. A fastener comprising a stud having a head and a neck, and a socket having a stud receiving aperture jaw means and operating means carried by said socket providing for alternate positions of rest of said jaw means in intersecting relation to said aperture and out of intersecting relation to said aperture. 95

7. A socket for separable fasteners providing jaw means and manipulative operating mechanism providing by successive similar manipulations for shifting of said jaw means alternately into operative and inoperative positions or rest. 100

8. A socket for separable fasteners presenting a stud-receiving aperture and a part rotatable about an axis parallel and eccentric to the axis of the stud-receiving aperture, said part presenting a plurality of stud-engaging jaws in spaced relationship. 105

9. A socket for separable fasteners presenting a stud-receiving aperture and a rotative part eccentrically mounted relative to the axis of the stud-receiving aperture and presenting a plurality of stud-engaging jaws in spaced relationship, and operating means providing for uni-direction, step-by-step partial rotation of said rotative part, successive positions of rest providing alternate 110 positioning of said jaws in stud-engaging and stud-releasing positions. 115

In testimony whereof, I have signed my name to this specification.

RALPH J. CARNEY.
